Primary Examiner — David Muller*Assistant Examiner* — Nathan Johnston(74) *Attorney, Agent, or Firm* — Chainey P. Singleton; Chalker Flores, LLP(57) **CLAIM**

The ornamental design for a tufted clothing hanger, as shown and described.

DESCRIPTION

FIG. 1 is an isometric view of a tufted clothing hanger showing my new design.

FIG. 2 is a front elevation view thereof.

FIG. 3 is a top plan view thereof, the bottom plan view being a mirror image; and,

FIG. 4 is a side elevation view thereof.

The features shown in broken lines depict environmental structure only and form no part of the claimed design.
